(57) **CLAIM**

We claim the ornamental design for a pole saw, as shown and described.

DESCRIPTION

FIG. 1 is a perspective view of a pole saw showing my new design;

FIG. 2 is a right-side view thereof;

FIG. 3 is a left-side view thereof;

FIG. 4 is a top view thereof;

FIG. 5 is a bottom view thereof;

FIG. 6 is a rear view thereof; and,

FIG. 7 is a front view thereof.

The dashed lines are included for illustrating environmental structure and form no part of the claimed design.
